UNITED STATES PATENT OFFICE.

LOESER KALINA, OF NEW YORK, N. Y.

SEWING OUTFIT.

1,099,252,

Specification of Letters Patent. Patented June 9, 1914.

Application filed July 18, 1913. Serial No. 779,698.

To all whom it may concern:

Be it known that I, LOESER KALINA, a citizen of the United States, and a resident of the city of New York, borough of Brooklyn, in the county of Kings and State of New York, have invented a new and Improved Sewing Outfit, of which the following is a full, clear, and exact description.

The object of the invention is to provide a new and improved sewing outfit of a very compact form for pocket use and arranged to hold a thimble, needles, sewing thread and pincushion.

In order to accomplish the desired result use is made of a shell open at both ends, one end having an inwardly-extending flange forming an interior seat for the bead on the base of a thimble, the bead of which extends through the corresponding open end of the shell; a cap for closing the other end of the shell and containing a pincushion and a needle case for containing needles and for holding spools of sewing thread, one end of the needle case abutting against the closed end of the thimble and the other end engaging the said cushion.

A practical embodiment of the invention is represented in the accompanying drawings forming a part of this specification, in which similar characters of reference indicate corresponding parts in all the views.

Figure 1 is a perspective view of the sewing outfit with the parts in assembled position; Fig. 2 is a sectional side elevation of the same; and Fig. 3 is a perspective view of the sewing outfit with the parts in disassembled position.

The shell A is preferably of cylindrical form and made of sheet metal, and the said shell is open at both ends, one end being provided with an inwardly-extending annular flange A' forming an interior seat for the bead B' on the base end of a thimble B adapted to project through the said end of the shell A, as plainly indicated in Figs. 1 and 2. The other end of the shell A is adapted to be closed by a shell cap C containing a pincushion D for supporting pins E, the cushion being engaged by one end of a needle case F containing needles G, preferably of various sizes. The needle case F is made of metal and is in tubular form closed at one end and adapted to be opened and closed at the other end by a suitable needle case cap F' adapted to abut with its inner edge on the annular bead F' formed inte-

grally on the case F. Exterioly onto the needle case F fit spools H containing sewing threads of different colors and textures; for instance, as shown in Fig. 2, the needle case is arranged to form a support for four spools of sewing thread, of which some are preferably of finer and some of coarser quality and of different colors to suit the pur- 65

chaser. The spools H are so arranged that the uppermost one fits against the bead F' while the lowermost one rests on the cushion D, that is, the aggregate length of the several spools corresponds approximately to the 70 length of the needle case from the closed end thereof to the bead F'. In order to hold the needle case F and the spools H from rattling, the pincushion D exerts a slight pressure against the closed end of the needle case F 75 and the corresponding end of the lowermost spool H, and for this use is made of a bayonet slot C' formed in the cap C and engaging a lug A' struck up in an inward direction on the corresponding end of the shell A. 80 The inner portion C' of the bayonet slot C' is inclined so that when the cap C is placed in position after the thimble B, the needle case F and the spools H are in position in the casing and the lug A' engages the bayonet slot C' and on turning the cap C finally engages the inclined portion C' then the cap C and with it the cushion D are moved lengthwise of the shell A so that the cushion D exerts the necessary pressure against the 85 closed end of the needle case F and the lower end of the lowermost spool H to securely hold the said parts in position within the shell A and the thimble B to prevent rattling of said parts. 90

When it is desired to make use of the thimble B, the needles G and sewing thread, then the operator first disconnects the cap C from the shell A to permit of removing the needle case F and the spools H and to finally allow withdrawing of the thimble B. The spools H can now be slipped off the needle case F and selection can be made as to the thread to be used, and a corresponding or desired needle G can be removed 100 from the needle case F by first removing the cap F' therefrom.

During the sewing operation other needles and other threads may be used and, if desired, some of the needles may be stuck in 110 the pincushion D until the sewing operation is completed, after which the needles are re-

placed in the case F and the latter closed by the cap F', and then the thimble B is reinserted in the shell A and the spools H placed on the needle case F and with the latter placed in position in the shell A with the cap F' abutting against the closed end of the thimble B, the shell A being preferably held in upside down position during this operation. The cap C is now replaced and 10 locked in position on the shell A to lock the thimble B, needle case F and the spools H in place in the shell, as above explained and shown in Figs. 1 and 2.

Having thus described my invention, I 15 claim as new and desire to secure by Letters Patent:

1. In a container for needles and spools, the combination of a shell open at both ends, one of the ends being provided with an inwardly extending flange, a conical head adapted to close the flanged end of the said shell, the said head being in the form of a thimble and provided at its base with an exterior bead adapted to be seated on the said flange, a removable shell cap adapted to close the other end of the said shell, and a case disposed centrally in the said shell and resting at one end on the said cap, the said case engaging the closed end of the said head at the inside thereof to hold the said head seated on the said shell flange, the said case being adapted to contain needles and being adapted to exteriorly support spools of sewing thread.
- 35 2. In a container for needles and spools, the combination of a shell open at both ends, one of the ends being provided with an inwardly-extending flange, a conical head adapted to close the flanged end of the said shell, the said head being in the form of a thimble and provided at its base with an ex-

terior bead adapted to be seated on the said flange, a removable shell cap adapted to close the other end of the said shell, the said cap being provided with a cushion, and a 45 case disposed centrally in the said shell and resting at one end on the cushion of the said cap, the said case engaging the closed end of the said head at the inside thereof to hold the said head seated on the said shell flange, 50 the said case being adapted to contain needles and being adapted to exteriorly support spools of sewing thread.

3. In a container for needles and spools, the combination of a shell open at both ends, 55 one of the ends being provided with an inwardly-extending flange, a conical head adapted to close the flanged end of the said shell, the said head being in the form of a thimble and provided at its base with an exterior bead adapted to be seated on the said flange, a removable shell cap adapted to close the other end of the said shell, a case 60 disposed centrally in the said shell and resting at one end on the said cap, the said case 65 engaging the closed end of the said head at the inside thereof to hold the said head seated on the said shell flange, the said case being adapted to contain needles and being adapted to exteriorly support spools of sewing 70 thread, and locking means for removably locking the said cap in closed position on the said shell and for drawing the shell inward.

In testimony whereof I have signed my 75 name to this specification in the presence of two subscribing witnesses.

LOESER KALINA.
